J. T. F. BANTJES.
TOOL HEAD AND HANDLE CONSTRUCTION.
APPLICATION FILED MAY 4, 1918.

1,336,185.

Patented Apr. 6, 1920.

Inventor:

J. T. F. Bantjes

UNITED STATES PATENT OFFICE.

JOHN T. F. BANTJES, OF KLERKSDORP, TRANSVAAL, SOUTH AFRICA.

TOOL HEAD AND HANDLE CONSTRUCTION.

1,336,185.

Specification of Letters Patent.

Patented Apr. 6, 1920.

Application filed May 4, 1918. Serial No. 232,674.

To all whom it may concern:

Be it known that I, JOHN THOMAS FREDERICK BANTJES, a subject of the King of Great Britain and Ireland, residing at 5 Klerksdorp, Transvaal Province, Union of South Africa, have invented a new and useful Tool Head and Handle Construction, of which the following is a specification.

My invention relates to a new and useful 10 tool and is particularly directed to the construction of the handle and its connection with the head of the tool.

In accordance with my invention, the head of the tool is provided with suitable 15 shoulders as by means of a groove or set of grooves, slot or set of slots cut or otherwise formed in the head and the end of the handle constructed in correspondence with such shoulders, *i. e.*, groove or set of grooves, or 20 slot or set of slots. In the preferred form of the invention the handle is positioned relative to such shoulders by sliding the handle relative to the head of the tool, and the handle fixed to the head of the tool by 25 means of rivets, screw bolts or the like.

Further features and objects of the invention will be more fully understood from the following description and the accompanying drawings, in which—

30 Figure 1 is a side elevation of a pick head embodying my invention; and

Fig. 2 is a perspective view of the same;

Fig. 3 is a perspective view of a handle 35 constructed in accordance with my invention and adapted to be fixed to the pick head shown in Figs. 1 and 2;

Fig. 4 is a perspective view of the assembled handle and pick head embodying my invention;

40 Fig. 5 is a perspective view of a head of a hammer embodying my invention; and

Fig. 6 is a perspective view of the assembled handle and head of hammer shown in Fig. 5;

45 Fig. 7 is a plan view of a screw bolt adapted for securing my handle to the head of a tool;

Fig. 8 is a perspective view of the head of an ax embodying my invention; and

50 Fig. 9 is a perspective view of the assembled ax and handle embodying my invention.

Referring to Figs. 1, 2 and 3, the pick 1, having the pointed ends 2, 3, is provided 55 with the grooves 4, shown positioned on the

opposite faces of the body of the pick 1, such grooves being formed dovetailed by means of the reentrant, oppositely disposed shoulders, shown integral with the central portion of the head 6 of the pick 1.

The handle 7 is provided with a bifurcated end formed by corresponding portions or lugs, 9, 9, oppositely disposed to provide the groove 8 adapted to receive the central portion 6 of the pick 1. The terminal portions or lugs 9, 9, are flared in correspondence with the reentrant angle of the shoulders 5, 5, whereby upon sliding the handle 7 in position on the head of the pick 1, the end faces of the terminal portions, or lugs 9, 9, make a tight fit with the prongs 5, 5, respectively. The handle may be provided with the openings 10, 10, corresponding to and adapted to register with the openings 11 in the head 6 of the pick 1, to receive a 75 screw bolt 12 (see Fig. 7) or other suitable means for affixing the handle 7 to the pick 1, as indicated in the assembled view shown in Fig. 4.

In Fig. 5 I have shown another form of 80 my invention namely, a claw hammer 14 having the head 15 and claws 16 and similarly provided at its portion 6 with the groove 4 formed by the shoulders 5. The portion 6 of the hammer 14 may be similarly provided with the openings 11, 11, as aforesaid. The assembled handle 7 and hammer 14 are shown in Fig. 6.

In Figs. 8 and 9, I have shown another form of my invention, namely an ax having the head 21 and the blade 22, and a body portion 6 provided with the groove 4 formed by similar reentrant oppositely disposed shoulders 5, 5. Fig. 9 shows the ax 20 and handle 7 assembled and provided with the 90 fastening means 12. The handle may be wholly or partly of tubular or socketed steel or like metal and when not wholly of metal, the length can be completed by inserting wood into the tube or socket.

The terminal portions or plugs of the handle, and the prongs of the heads of the tools may be cut, molded or otherwise formed.

The one-piece or integral construction of 105 the connection of the handle with the head attains the important advantage of insuring the life of the handle for a period at least equal to the period of the head of the tool and by means of the construction of the co- 110

acting connecting features of the head and handle, slipping of one relative to the other is entirely obviated.

I claim—

- 5 1. In a tool, the combination of a head having dovetailed recesses on opposite sides thereof, a metallic handle with bifurcated end, the two legs of said bifurcated end being shaped to fit snugly within the dove-tailed recesses of the head, and means for securing said handle to said head.
- 10 2. In a tool, the combination of a head having substantially dovetailed recesses on

opposite sides thereof, a tubular or hollow metallic handle, one end of which is bifurcated and the two legs at said bifurcated end being shaped to fit snugly within said recesses of the head, and means for securing said handle to said head substantially as described.

Signed at Johannesburg this the 5th day of March, 1918.

JOHN T. F. BANTJES.
